US00D842310S

(12) **United States Design Patent** (10) Patent No.: **US D842,310 S**
Ford (45) Date of Patent: ** Mar. 5, 2019

(54) **DISPLAY SCREEN OR PORTION THEREOF WITH A GRAPHICAL USER INTERFACE INPUT SELECTOR**

(71) Applicant: **AMAZON TECHNOLOGIES, INC.**, Seattle, WA (US)

(72) Inventor: **Keith W. Ford**, Seattle, WA (US)

(73) Assignee: **AMAZON TECHNOLOGIES, INC.**, Seattle, WA (US)

(**) Term: **15 Years**

(21) Appl. No.: **29/576,333**

(22) Filed: **Sep. 1, 2016**

(57) **CLAIM**

The ornamental design for a display screen or portion thereof with a graphical user interface input selector, as shown and described.

DESCRIPTION

FIG. 1 is a view of a first embodiment of a graphical user interface for a display screen or a portion thereof; and, FIG. 2 is a view of a second embodiment of a graphical user interface for a display screen or a portion thereof. The broken lines showing a display screen or portion thereof and elements of the graphical user interface illustrate portions of the article and form no part of the claimed design.

1 Claim, 2 Drawing Sheets
